UNITED STATES PATENT OFFICE.

WALTER O. AMSLER, OF PITTSBURGH, PENNSYLVANIA.

ANNEALING FURNACE OR LEER.

1,415,622.

Specification of Letters Patent. Patented May 9, 1922.

Application filed May 21, 1920. Serial No. 383,258.

To all whom it may concern:

Be it known that I, WALTER O. AMSLER, a citizen of the United States, residing at Pittsburgh, in the county of Allegheny and 5 State of Pennsylvania, have invented certain new and useful Improvements in Annealing Furnaces or Leers, of which the following is a specification.

My invention relates to an annealing 10 furnace or leer and more particularly to a new and improved roof structure for the annealing chamber of such furnaces.

As heretofore generally built the roof of the annealing chamber has been constructed 15 of tiles assembled to form an arch, the ends of the arch resting upon the side walls of the annealing chamber; in some instances the roof has been formed flat and metallic beams, hangers, etc. employed for supporting 20 the roof.

For some purposes it is believed that a flat roof is desirable, and the present invention is directed to such a construction, omitting however the objectionable features of 25 construction such, for example, as metallic supporting members heretofore employed.

In the accompanying drawings, which illustrate applications of my invention,

Figure 1, is a vertical sectional view of 30 an annealing furnace or leer embodying my invention;

Figure 2, a longitudinal sectional view of a portion of an annealing furnace, the section being taken on line 2—2 of Figure 1;

Figure 3 a detail vertical sectional view 35 showing a modified construction, the arched members formed integral with the flat tiles;

Figure 4 a detail longitudinally extending sectional view of the form of Figure 3;

Figure 5 a detail sectional view showing 40 still another form of roof construction embodying my invention.

Referring to the drawings, 2 designates 45 the front wall of an annealing furnace or leer, 3 the top wall and 4 the side walls of the furnace.

In the furnace illustrated the combustion 50 chamber 5 is located at the top of the structure and between the roof of the annealing

chamber 6 and the furnace roof or top wall 3. Fuel is admitted from a burner through an opening 7 in the roof. It will of course be understood that a plurality of top combustion chambers may be employed. Side 55 flues disposed between the furnace side walls 4 and the side walls 8 of the annealing chamber communicate with longitudinally extending flues 9. The bottom of the furnace indicated by 10 is supported upon a 60 series of cross-beams 11 and 12 designates a continuous conveyor designed to pass through the annealing chamber for conveying the articles to be annealed. As the furnace per se does not constitute the subject matter of the present invention I consider it unnecessary to further describe the 65 same.

The annealing chamber is formed between the interlocked bottom tiles 13, the side wall 70 tiles 8 and the roof structure.

The roof of the annealing chamber constitutes an important and characteristic feature of the present invention and as illustrated and as preferred, includes a plurality of horizontally disposed flat tile members and a plurality of supporting or strengthening members all made of suitable refractory materials. The members constituting the roof are assembled in interlocked 75 relationship and may assume different forms, this is particularly true of the supporting elements or members.

In the form of Figure 1 the supporting or reinforcing members 14 each includes a 85 wedge shaped body portion *a* having a curved or arched upper edge and an enlargement or head *b*. In this construction the flanges *c* of the flat tiles 15 rest upon the heads *b* of members 14, and when assembled, 90 form an interlocked structure. 16 designates a series of skew blocks forming the upper edge of the side walls of the annealing chamber and against which the end members 14 bear. The tiles 14 are provided 95 along their edges with tongues and grooves.

In the form of Figure 3, the reinforcing members 14^a are formed integral with the flat tile members 15^a, and in the form of Figure 5, the members 14^b, like the mem- 100

bers 14 of the form of Figure 1 are separable or independent members. In this last mentioned form, however, the members 14^b extend downwardly instead of upwardly as in the other forms.

5 What I claim is:

1. A flat roof structure including a series of flat tiles and a series of arched members assembled in interlocked relationship.
- 10 2. A flat roof structure including horizontally disposed flat tiles and tile supporting members formed of refractory materials.
- 15 3. A flat roof structure including horizontally disposed flat tiles and arched tile supporting members formed of refractory material.
4. A flat roof structure including flat tiles and tile supporting members formed

of refractory material and assembled in interlocked relationship.

20

5. A flat roof structure including a series of flat tiles and a series of separable tile supporting members all formed of refractory material.

6. A flat roof structure including a series of horizontally disposed flat tiles of refractory material, a series of separable wedge shaped supporting members of refractory material, said tiles and members assembled in interlocked relationship.

25

In testimony whereof I affix my signature in presence of two witnesses.

30 WALTER O. AMSLER.
